UNITED STATES PATENT OFFICE.

EDWARD LENKE, OF CUYAHOGA FALLS, OHIO, ASSIGNOR TO FRANK T. LAHEY, OF AKRON, OHIO.

COLLAPSIBLE BOX.

1,263,575.

Specification of Letters Patent. Patented Apr. 23, 1918.

Application filed December 11, 1916. Serial No. 136,246.

To all whom it may concern:

Be it known that I, EDWARD LENKE, a citizen of the United States, residing at Cuyahoga Falls, in the county of Summit 5 and State of Ohio, have invented new and useful Improvements in Collapsible Boxes, of which the following is a specification.

This invention has relation to improvements in collapsible boxes or shipping pack-10 ages. The primary object of the invention is to provide a box or package, the side and end forming members of which are pivotally connected with the bottom member so that the box or package may be readily collapsed, 15 when necessary and equally easily expanded to its open or operative position. More particularly the invention contemplates a box or package comprising a bottom member having its marginal portions provided with 20 means arranged to form pivotal connections with the side and end members to permit the latter members to be arranged in their open positions to form the box or package and to be folded inwardly upon each other 25 in the collapsing of the box or package. Furthermore, the invention contemplates so forming the pivotal connections between the bottom and side members that unintentional separation of said members is impos-30 sible to thereby prevent the accidental loss of any one of said members, when for any reason the box or package is in its collapsed condition. The means employed for pivotally connecting the various members of the 35 box or package together are supplemented by means to provide interengagement be-40 tween the side and end members when the box or package is in its open or expanded condition, to hold these members in posi-45 tion and to stiffen and strengthen the entire device. In connection with said box or package a cover is provided which is so constructed that when the box or package is in its expanded or open position it constitutes 50 a closure member therefor and may be used as a receptacle for the box or package when the latter is in its collapsed condition.

With the foregoing and other objects in view, the invention consists in the novel construction, combination and arrangement of 55 parts constituting the invention to be hereinafter specifically described and illustrated in the accompanying drawings which form a

part hereof wherein is shown the preferred embodiment of the invention, but it is to 55 be understood that changes, variations and modifications can be resorted to which come within the scope of the matter hereinafter claimed.

In the drawings in which similar refer-60 ence numerals indicate like parts in the dif-ferent figures,

Figure 1 is a perspective view of a col-65 lapsible box or shipping package embodying the present invention shown in its open or expanded position.

Fig. 2 is a view similar to Fig. 1 showing the box or shipping package in its collapsed position.

Fig. 3 is a vertical, transverse, sectional 70 view taken approximately on line 3 of Fig. 1.

Fig. 4 is a view similar to Fig. 3 taken approximately on line 4 of Fig. 1.

Fig. 5 is a transverse sectional view show-75 ing the upper portions of the walls 2 and 3 with the cover or closure member in posi-tion therein.

Fig. 6 is a transverse sectional view of the box in its collapsed position taken approxi-mately on line 6 of Fig. 2. 80

Fig. 7 is a view similar to Fig. 6 taken approximately on line 7 of Fig. 2.

Fig. 8 is a fragmentary sectional view of the device shown in Fig. 9, and

Fig. 9 is a perspective view showing the 85 upper portion of coadjacent side and end members of the box, showing a means for uniting the two when the box is in its open or expanded position.

Referring to the drawings in detail the 90 box embodies a lower or bottom member 1, end members 2 and 3, side members 4 and 5 and a closure member 6. The bottom member comprises a sheet 7 preferably of 95 non-metallic material such as wood or heavy cardboard and secured to the marginal por-tions of which is an L-shaped reinforcing marginal angle member preferably formed of metal and comprising an upwardly pro-jecting portion or flange 8 and a lower 100 portion or flange 9, the former arranged in abutting relation with the side and end edges of the sheet of material 7 and pro-jecting upwardly therefrom and with the part 9 arranged in lapping engagement with 105 the marginal portions of the under face of

the sheet 7. The reinforcing angle member 8-9 is secured to the sheet 7 by holding means 11.

It may be stated that the various side, 5 and end forming members, are of such size and so connected with the bottom member that they may be successively folded inwardly one upon another and in approximate parallelism with the bottom member 10 and when so folded, inclosed by the closure member to be described for compactness in shipping and storage. It is contemplated that the end member 2 will be first folded inwardly which successively is 15 followed in turn by the members 3, 4 and 5.

Secured to the inner face of the flange 8 at one end of the device, by means of the holding members 11 is an end hinge forming strip 12 the lower portion of which is 20 arranged in close contact with the inner face of the flange 8, and is positioned between said flange and one edge of the sheet 7 forming a part of the lower member 1. The upper portion of the strip 12 is bent inwardly at right angles to form a horizontal portion 13 with its lower face arranged in lapping engagement with the upper face of the sheet 7 and the inner part of the part 13 is bent upwardly to form a portion 14 25 parallel with and arranged in spaced relation with respect to the flange 8. Extending horizontally from the portion 14 is a flange 15 parallel with the portion 13 and arranged in spaced relation thereto. The flange 15 is less in width than the portion 30 13 to provide a slot 16 extending between the edge of the flange 15 and the flange 8. The upright portion 14 of the hinge forming member 12 is approximately equal in height 35 to the transverse width of the end forming member 2.

The end forming member 2 comprises a sheet of suitable material such as wood or cardboard of the proper size for the purpose required and is provided along its outer lower marginal portion with a strip 45 17 preferably formed of thin metallic material such as sheet metal. This strip is parallel to and projects beyond the lower edge of the member 2 and is there provided with an integral lateral flange 18 arranged at right angles to the portion 17. This flange 18 is provided with a marginal flange 19 arranged at right angles thereto. The flange 19 is less in width than the distance 50 between the flange 13 and the end 2 to thereby provide a space 20. The marginal strip 17 provided with the right angled flange 18 and flange 19 are adapted to form 55 a combined reinforcement and hinge forming member substantially hook-shaped which is arranged to cooperate with the hinge forming member 12 carried by the flange 8, and to sufficiently interlock therein 60 to prevent the unintentional withdrawal of

the member 2 and yet permit said member to be folded inwardly and downwardly upon the bottom member as shown in Figs. 6 and 7. The slots 16 and 20 are of sufficient width to permit the swinging or shifting 70 of the member 2 into the position shown in Fig. 6 wherein the member 2 is superposed upon the upper face of the sheet 7.

The flange 8 on the opposite end of the sheet 7 is provided with a hinge forming member 21, similar in all respects to the hinge forming member 12, with the exception that it is elevated to a position higher on the flange 8, than is the hinge forming member 12 to compensate for the thickness 80 of the member 2 and permit the inward swinging of the member 3 into lapping engagement with the upper face of the member 2. The member 3 is provided with a marginal strip 22, similar in all respects 85 and formation to the marginal reinforcing strip 17 on the member 2 and this strip 22 is provided with a depending hinge forming portion complementary to the strip 21 and the operation of moving the member 3 to its 90 open or closed position is identically similar to the operation described with reference to the member 2 and hence it is believed a further description thereof is unnecessary. However, when the member 3 is moved to 95 its collapsed position it will rest upon and lap the upper face of the member 2. The upper edge of the member 2 is provided with a reinforcing strip 23 and the member 3 with a reinforcing strip 24. These 100 two strips 23 and 24 constitute binding strips for stiffening the members and preventing wear and injury thereto. The marginal flange 8 is provided, at one side of the device, with a hinge forming member 25, 105 similar to the strip 12 but arranged at a sufficient distance above the bottom sheet 7 equal to the combined thickness of the members 2 and 3. The member 4 is provided with a hinge forming member 26, similar to the member 22, arranged to cooperate with the member 25 in identically the same manner as the two hinge forming members 21 and 22 cooperate with each other with respect to the side forming member 3. In order to support the hinge forming portion 25 I interpose a strip of suitable material 110 27 between the member 25 and the bottom sheet 7 as clearly shown in Figs. 4 and 7. The flange 8 on the remaining opposite side 115 of the device is provided with a hinge forming member 31, similar to the hinge forming members 12, 21 and 26, but elevated above the bottom sheet 7 a distance sufficient to permit the infolding of the member 5 over the members 2, 3 and 4, so that when the side forming member 5 is folded to its inner or closed position it will seat upon the upper 120 face of the member 4 as shown in Fig. 7. The member 5 is provided with a marginal 125

strip 32, having a hinge forming portion 33 similar to the hinge forming member on the lower face of the member 2, and it is arranged to coöperate with the member 31 to permit the free infolding of the member 5. The upper marginal edges of the members 4 and 5 are provided with binding strips 34 and 36 respectively which are similar to the binding strips 23 and 24. The hinge forming portion 31 on the flange 8 which coöperates with the hinge member 32 of the member 5 is supported by means of an interposed strip 37 of suitable material. The lateral marginal edges of the side forming member 4 are provided with strips of strengthening material, preferably of sheet metal, in the form of a right angle and designated in the drawings by the reference numeral 40. These strips are secured to the member 4 by holding means such as rivets 41 and the member 5 is provided with a pair of similar strips 42 for a similar purpose. It will be noted that the various members 2, 3, 4 and 5 vary in their vertical dimensions, in that the member 2 is wider than the member 3, and the latter is wider than the member 4 and the member 4 is wider than the member 5 so as to permit the infolding or successive superimposition of the various members into the positions shown in Figs. 6 and 7. When the members 2 and 3 are swung or moved to their open or expanded position they abut against the right angled reinforcing strips 40 and 42 on the members 4 and 5 and this engagement stiffens the general structure of the box when in its open position. In order to lock the various members in their open or expanded position there is provided on the inner marginal portions of contiguous side and end forming members, a pair of complementary strips 50, each attached to its respective members by holding means 51, and each provided with an eye or a tubular inner end 52, so positioned that the tubular ends on contiguous members may be in vertical registration when the members are moved to their open position to permit the insertion of a pin or similar locking means 53 therein as shown in Fig. 9, for holding the end and side forming members in their open or expanded position. I provide a cover for the device which preferably comprises a sheet of suitable material 60 provided with marginal reinforcing strips 61 formed to provide marginal channels 62 from which extend downwardly projecting outer flanges 63. The channel forming portions 62 are adapted to receive the upper marginal portions of the members 2 to 5 inclusive and with the flanges 63 arranged in lapping engagement with the outer faces of these members when the box is in its open or expanded condition. The flanges 63 are of such width that when the box is in its collapsed position the flanges 63 will lap the

outer faces of the flanges 8 and form a telescopic engagement therewith for forming a completely closed package with the sheet 60 seated on the upper face of the member 5 as shown in Figs. 6 and 7. The box may be kept in its collapsed position by means of a binding wire 64, as shown in Fig. 2, and the sides and ends may be kept in open position by passing wires 65 through suitable apertures in the corner portions or flanges 63 and the reinforcing strips 40 and 42, as shown in Fig. 1. If desired, suitable seals 66 may be employed for preventing unauthorized tampering with the box, either when the latter is in its collapsed or expanded position. In Fig. 1 the position of the end member 2, during its movement from its open position to its closed position is indicated in dotted lines.

I claim:

1. A shipping package in the form of a rectangular collapsible box comprising a bottom, side and end members, an angle member having an upstanding marginal flange surrounding said bottom member, a hinge member forming strip positioned on the inner face of each portion of said flange, said hinge member forming strip being hook-shaped in cross section to provide a rectangular channel arranged inwardly of said flange and having a free longitudinal edge slightly spaced from said flange, each of said side and end members being provided on one edge with a complementary hinge member forming strip, hook-shaped in cross section providing a rectangular channel and arranged to interengage in one of the first described channels and thereby form a hinge connection therewith to permit the free successive infolding of said members into parallelism with the upper face of said bottom member, and a cover for said device arranged to form a closure therefor irrespective of whether the same is in its open or closed position.

2. A shipping package in the form of a rectangular collapsible box comprising a bottom, side and end members, an angle member having an upstanding marginal flange surrounding said bottom member, a hinge member forming strip positioned on the inner face of each portion of said flange, said hinge member forming strip being hook-shaped in cross section to provide a rectangular channel arranged inwardly of said flange having a free longitudinal edge slightly spaced from said flange, each of said side and end members being provided on one edge with a complementary hinge member forming strip, hook-shaped in cross section providing a rectangular channel and arranged to interengage in one of the first described channels and thereby form a hinge connection therewith to permit the free successive infolding of said members into par-

allelism with the upper face of said bottom member, and interengaging means carried by coadjacent side and end members for holding the side and end forming members in their open position.

3. A shipping package in the form of a rectangular collapsible box comprising a bottom, side and end members, an angle member having an upstanding marginal flange surrounding said bottom member, a hinge member forming strip positioned on the inner face of each portion of said flange, said hinge member forming strip being hook-shaped in cross section to provide a rectangular channel arranged inwardly of said flange and having a free longitudinal edge slightly spaced from said flange, each of said side and end members being provided on one edge with a complementary hinge member forming strip, hook-shaped in cross section providing a rectangular channel and arranged to interengage in one of the first described channels and thereby form a hinge connection therewith to permit the free successive infolding of said members into parallelism with the upper face of said bottom member, the hinge connection of each superimposed infolded member being farther removed from said bottom member than the hinge connection of the next preceding infolded member, to thereby provide and compensate for the thickness of the preceding member and permit the orderly superimposition of said members in parallelism, and a cover for said device arranged to form a closure therefor irrespective of whether the same is in its open or closed position.

In testimony whereof I have hereunto set my hand in presence of two subscribing witnesses.

EDWARD LENKE.

Witnesses:

4. A shipping package in the form of a
40 rectangular collapsible box comprising a

bottom, side and end members, an angle member having an upstanding marginal flange surrounding said bottom member, a hinge member forming strip positioned on the inner face of each portion of said flange, 45 said hinge member forming strip being hook-shaped in cross section to provide a rectangular channel arranged inwardly of said flange and having a free longitudinal edge slightly spaced from said flange, each 50 of said side and end members being provided on one edge with a complementary hinge member forming strip, hook-shaped in cross section providing a rectangular channel and arranged to interengage in one of the first 55 described channels and thereby form a hinge connection therewith to permit the free successive infolding of said members into parallelism with the upper face of said bottom member, the hinge connection of each superimposed infolded member being farther removed from said bottom member than the hinge connection of the next preceding infolded member, to thereby provide and compensate for the thickness of the preceding 60 member and permit the orderly superimposition of said members in parallelism, interengaging means carried by coadjacent side and end members for holding the side and end members in their open position, and a 65 cover for said device arranged to form a closure therefor irrespective of whether the same is in its open or closed position. 70

In testimony whereof I have hereunto set my hand in presence of two subscribing witnesses. 75

EDWARD LENKE.
